UNITED STATES PATENT OFFICE.

JOSEPH ETIENNE L'HEUREUX, OF MANVILLE, RHODE ISLAND.

SASH-LOCK.

1,339,362.

Specification of Letters Patent.

Patented May 4, 1920.

Application filed April 11, 1919. Serial No. 289,457.

To all whom it may concern:

Be it known that I, JOSEPH E. L'HEUREUX, a citizen of Great Britain, residing at Manville, in the county of Providence and State 5 of Rhode Island, have invented new and useful Improvements in Sash-Locks, of which the following is a specification.

This invention relates to windows, particularly to sash locks, and has for its object 10 the provision of a lock whereby storm windows or screen frames may be secured within the window frame.

An important object is the provision of 15 a sash lock which includes a movable member eccentrically mounted whereby upon rotation thereof it will be caused to extend behind a retaining strip, this movable member being also formed cam-shape in cross section whereby upon rotation thereof the 20 storm window or screen frame will be drawn closely into engagement with the retaining strip whereby to hold the same not only against dislocation but also against any possible rattling.

Another object is the provision of a 25 device of this character which is so constructed that when a storm sash is removed to permit its replacing by a screen, no gap will be left remaining in the retaining strip, a 30 disadvantage present with the ordinary forms of window fasteners for this purpose.

An additional object is the provision of 35 a device of this character which will be simple and inexpensive in manufacture, which may be quickly and easily installed or removed, which will be durable in use, and a general improvement in the art.

With the above and other objects and advantages in view, the invention consists in 40 the details of construction to be hereinafter more fully described and claimed, and illustrated in the accompanying drawings, in which—

Figure 1 is a front elevation of a window 45 frame having a storm sash engaged therein and secured in position by a plurality of my fasteners,

Fig. 2 is a fragmentary front elevation 50 of a window frame showing a storm sash engaged therein and having my fastener in position prior to locking the same,

Fig. 3 is a similar view showing the fastener in locking position,

Fig. 4 is a cross sectional view on the line 55 4—4 of Fig. 2, showing the cam edge of the movable member,

Fig. 5 is a perspective view of the movable member,

Fig. 6 is a detail sectional view showing 60 the interior of the fastening member and illustrating the springs therein for holding the movable member in selected position,

Fig. 7 is a fragmentary view looking at 65 the face of the frame and showing the coöperating fastening member recessed thereinto,

Fig. 8 is a perspective view of the co-operating fastening member.

Referring more particularly to the drawings, the letter A designates a window frame 70 upon the sides B of which are secured longitudinally extending retaining strips C. The letter D designates a storm sash fitting within the frame A and adapted to be closely engaged against the strips C.

In carrying out my invention I provide 75 the sides of the frame A with recesses 10 within which are disposed members 11 which fit snugly within the recesses and which have end extensions 12 disposed beneath the 80 strips C. The strips C are also cut away, as shown at 13, to accommodate the body portions 14 of the members 11 which, when in position, are co-extensive with the severed ends of the strips C so that the effect will 85 be the same as if the strips C were not interrupted or cut away. These members 11 are formed of metal and are adapted to be 90 engaged by movable members to be described.

Secured upon the sash D opposite the retaining members 11 are casings 15 which are secured in place by means of screws 16 passing through attaching ears 17. Each casing is formed hollow and is provided in 95 its outer face with a circular hole 18 through which passes the stem 19 of a movable member 20 having a handle 21. This movable member 20 has a substantially semicircular head and the stem 19 is eccentric with respect thereto. A screw 22 extends from the bottom portion of the casing 15 and is threaded into the inner end of the stem 19 for retaining the movable member 20 in 100 position while permitting partial rotation thereof.

In order that the movable member 20 may be held in either of these two positions, the stem 19 is provided upon opposite sides with flattened portions 23 which are engaged 110 by a pair of spaced leaf-springs 24 which are secured at one end within the casing 15.

When the sash B is placed in position the members 20 will be in such position that the substantially straight edges 25 thereof will be disposed toward the strips C and 5 will be in non-obstructing relation thereto. In order to secure the sash in position, it is then necessary to grasp the handle 21 and give the movable member 20 a further rotation whereupon by virtue of the eccentricity of the stem 19 the head portion of these movable members will engage over the member 11 interposed in the strips C. It will be observed that each movable member 10 is tapered from the straight edge 25 at 15 the end opposite the handle 21 whereby to provide a relatively thin edge which will initially engage the member 11 so that upon movement of the member 20 to its initial position a wedge action will be produced for 20 drawing the sash firmly into engagement with the strips C.

From the foregoing description and a study of the drawings it will be apparent that I have thus provided a very simple and 25 efficient sash fastener which may be used for securing storm windows or screen frames in position and which will not only retain them in position against accidental displacement but which will also prevent rattling.

30 While I have shown and described the preferred embodiment of my invention, it is of course to be understood that I reserve the right to make such changes in the form,

construction, and arrangement of parts as will not depart from the spirit of the invention or the scope of the subjoined claim. 35

Having thus described my invention, I claim:—

In combination with a sash and window frame provided upon its inner faces with 40 longitudinally extending retaining strips having cut out portions, locking means comprising retaining members in the form of plates sunk into the inner faces of the window frame and having extensions filling said 45 cut out portions, and fastening members carried by the sash and coöperating with said retaining members, each of said fastening members comprising a casing, a latch member having a stem revoluble within said casing and including a head mounted eccentrically upon the stem whereby upon rotation of the latch member said head will be extended into engagement with one face of 50 the associated extension, a handle formed integrally upon the head, said stem having diametrically opposite flattened portions, and a substantially U-shaped leaf-spring disposed within the casing and having its bight portion and terminals prevented from 55 movement, the arms of said spring engaging the flattened portions of the stem for holding said latch member in either operative or inoperative position.

In testimony whereof I affix my signature. 60
JOSEPH ETIENNE L'HEUREUX. 65
